UNITED STATES PATENT OFFICE.

AINSWORTH J. HAGUE, JR., OF RED BANK, NEW JERSEY.

DESIGN FOR A NEEDLEBOOK.

Application filed November 30, 1925. Serial No. 15,587. Term of patent 3½ years.

To all whom it may concern:

Be it known that I, AINSWORTH J. HAGUE, Jr., a citizen of the United States, residing in Red Bank, county of Monmouth, State of New Jersey, have invented a new, original, and ornamental Design for a Needlebook, of which the following is a specification, reference being had to the accompanying drawing, forming part thereof.

The figure is a perspective view of a needle book showing my new design.

I claim:

The ornamental design for a needle book substantially as shown.

AINSWORTH J. HAGUE, JR.
